BALANCED VANE PUMP

Warren R. Tucker, Dayton, Ohio, assignor to The
Hydraulic Development Corp. Inc., Wilming-
ton, Del., a corporation of Delaware

Application October 21, 1941, Serial No. 415,921

1 Claim. (Cl. 103—120)

This invention relates to fluid pumps and particularly to fluid pumps of the vane type.

When using fluid pumps of the vane type for delivering fluid under relatively high pressures considerable unbalance of pressure is developed within the pump causing an unbalanced condition upon the bearings supporting the working structure. The pressure developed within the pumps acts upon the surfaces of the pump exposed to the pressure to cause a resultant of force which is transverse to the axis of rotation of the pump so that one side of the bearing supporting the rotating elements of the pump carries a greater load.

It is an object of this invention to provide a pump of the rotary type wherein the forces acting upon the rotating elements of the pump are balanced so that the load carried by the bearings of the pump is evenly distributed over the entire surface of the bearings.

It is another object of the invention to provide a pump of the type having a rotating pumping element operating within a cylinder in an eccentric manner with respect to the cylinder which is constructed and arranged in a manner that the forces acting transversely with respect to the axis of rotation of the rotary element are balanced to prevent a heavy load upon one side of the supporting bearings for the rotating element.

It is another object of the invention to provide a rotary pump wherein there is provided a plurality of rotating pumping elements which are arranged with respect to one another in a manner that the forces developed within the respective pumps acting transversely to the axis of rotation of the pumps balance one another to evenly distribute the load upon the bearings of the pump.

Another object of the invention is to provide a fluid pump having a plurality of rotary pumping elements which are disposed upon a common drive shaft in a manner that the transversely acting forces developed within the pumps balance each other to prevent unbalance of load upon the bearings for the drive shaft.

It is another object of the invention to provide a fluid pump having a plurality of rotary pumping elements which are secured together for concomitant rotation, and are arranged with respect to one another in a manner that the transversely acting forces developed by the pumping action of the respective pumping elements balance each other.

It is another object of the invention to pro-

vide a liquid pump of the rotary type having a plurality of pumping elements which are constructed and arranged for positive displacement of liquid and are positioned with respect to one another in a manner to balance the forces acting transversely of the pumping elements to eliminate unbalance of load upon the bearings of the pump structure.

It is a more specific object of the invention to provide a liquid pump having a plurality of rotary pumping elements wherein the pumping elements are arranged in substantial axial alignment and the pumping elements adjacent opposite ends of the central pumping element are of less volumetric capacity than the central pumping element and are disposed eccentrically 180° from the eccentric position of the central pumping element whereby the transversely acting forces developed within the pumps are balanced.

It is another object of the invention to provide a variable delivery fluid pump constructed and arranged in accordance with the foregoing objects.

It is another object of the invention to provide a fluid pump of the vane type constructed and arranged in accordance with the foregoing objects.

It is still another object of the invention to provide a pump structure to produce the results set forth in the foregoing objects.

Further objects and advantages will become apparent from the following description and the drawings.

In the drawings:

35 Figure 1 is a side elevational view of a pump constructed and arranged in accordance with the teachings of this invention.

Figure 2 is a horizontal cross-sectional view taken along line 2—2 of Figure 1.

40 Figure 3 is a vertical cross-sectional view taken along line 3—3 of Figure 1.

Figure 4 is a schematic cross-sectional view of the pumping elements of the pump of this invention showing the relative positions of the pumping elements with respect to one another and the direction and magnitude of the forces developed within the pump to show the manner in which the forces balance each other.

50 Figure 5 is a view similar to Figure 4 but shows the pumping elements in a slightly different position from that shown in Figure 4 to indicate the manner in which the forces developed within the pump can shift and still maintain their balanced condition.

55 In this invention the pump is particularly

adapted for use for delivering liquid under high pressure. When positive displacement liquid pumps are used to produce high pressures for use in hydraulic actuating systems considerable unbalance of forces is developed within the pump structure. This is particularly true of rotary pumps wherein a rotor member is rotationally driven within a cylinder in a manner that liquid is drawn into the cylinder upon one side thereof and is discharged through a port which is remote from the port of intake. When speaking of rotary type pumps, it is to be understood that such language includes pumps of the vane type, that is, those pumps having a rotating element within a cylinder which carries a plurality of radially extending vanes for engaging the cylinder wall as well as that type of pump which can be considered a truly rotary pump wherein the rotor itself engages the cylinder wall.

This invention is also applicable to a radial type pump since a plurality of groups of cylinders can be arranged with respect to one another in a manner that the forces developed within the cylinders can oppose one another.

The principles of this invention are particularly disclosed and described in connection with a vane type rotary pump. However, the principles of the invention are not so limited and the disclosure only shows one form of a pump wherein the principles of the invention can be applied.

The pump 10 consists of a casing 11 which is substantially U-shaped and having end walls 12 and 13 thereby providing a hollow interior 14. A bottom wall or closure plate 15 is secured to the casing 11 by means of suitable bolts 16.

The end walls 12 and 13 are provided with openings 17 and 18 respectively for receiving bearings 19 and 20 respectively. The bearings 19 and 20 support the rotor 25 which will be hereinafter more specifically described. The rotor 25 has a drive shaft 21 extending from one end thereof which is journaled within the bearing 19 and has a bearing portion 22 upon the opposite end thereof which is journaled in the bearing 20. As shown in the drawings, the bearings 19 and 20 are of the ball type. However, the specific structure of the bearing may be considerably altered and it is these bearings which are to be protected by the balancing of the forces within the pump.

End closure plates 23 and 24 are provided for the openings 17 and 18 respectively and are secured to the casing 11 by means of the bolts 26 and 27. The closure plate 23 is provided with an opening 28 through which the drive shaft 21 extends. A suitable seal 29 is provided between the drive shaft 21 and the opening 28 in the closure plate 23. The closure plate 24 is provided with an insert 30 threadedly engaging the plate 24 to permit removal thereof in order to obtain access to the interior of the casing 11.

The pump is constructed and arranged in a manner to provide three pumping units 31, 32 and 33. The pumping element 32 has a volumetric capacity which is double that of either of the pumping units 31 or 33 so that the force developed within the pumping unit 32 will be double that developed within either of the pumping units 31 or 33. Each of the pumping elements 31, 32 and 33 is provided with a plurality of vanes 34, 35 and 36 positioned as shown in Figure

3 with respect to the positioning of the individual elements of the pump units.

The rotor 25 consists of a plurality of elements which are secured together to produce a composite rotor constructed and arranged to cooperate with a plurality of cylinders 37, 38 and 39.

Referring to Figure 3, each of the cylinders 37, 38 and 39 are substantially rectangular in contour and have parallel walls 40 and 41 which slidably engage parallel walls 42 and 43 respectively of the casing 11, the walls 42 and 43 being provided upon the wall surface of the interior 14. The cylinders 37, 38 and 39 are provided with suitable bores 44, 45 and 46 respectively within which the vanes 34, 35 and 36 respectively are adapted to be rotated by means of the rotor 25. The rotor 25 is a composite structure composed of a cylindrical flange 47 having a cylindrical ring 48 of smaller diameter as an integral part thereof whereby a shoulder 49 is provided for engaging the face 50 of one side of the cylinder 39. The cylindrical or annular ring 48 extends through the bore 46 of the cylinder 39 and has a cylindrical flange 51 secured thereto by means of a plurality of bolts 52, thereby providing a shoulder 53 which engages the face 54 of the cylinder 39. The flange 51 carries an integral annular ring 55 which extends through the cylinder 38. The shoulder 56 engages the face 57 of the cylinder 38 while the shoulder 58 of an annular ring 59, secured to the annular ring 55 by means of a plurality of bolts 60, engages the face 61 of the cylinder 38. An annular ring 62 extends through the bore 44 of the cylinder 37 and engages the annular ring 59 to provide a shoulder 63 which engages the face 64 of the cylinder 37. The annular ring 62 is provided with an annular flange 65 to produce a shoulder 66 which engages the face 67 of the cylinder 37. The annular ring 62 is secured to the annular ring 59 by means of a plurality of bolts 68. These various elements heretofore described are thus associated with respect to one another to produce a composite rotor which cooperates with the cylinders 37, 38 and 39 to provide the plurality of pumping elements 31, 32 and 33.

The annular rings 48, 55 and 62 of the rotor 25 are provided with slots within which the vanes 34, 35 and 36 respectively are slidably carried. As shown in Figure 3, the slots 69 extend through the annular rings 48, 55 and 62 so that the outer ends of the vanes carried therein engage the bores 44, 45 and 46 of the respective cylinders.

The inner ends of the vanes 34, 35 and 36 extend within the cylindrical bores 44, 45 and 46 of the annular rings 62, 55 and 48 respectively. The inner ends of the vanes 34, 35 and 36 engage the surface of conical shaped plugs 73, 74 and 75, the inner edges of the vanes being provided with an angular surface to cooperate with the surfaces of the plugs. The plugs 73, 74 and 75 thus provide means for insuring engagement of the vanes 34, 35 and 36 with their respective cylinder walls 44, 45 and 46.

To insure engagement of the surfaces of the plugs 73, 74 and 75 with the respective cooperating vanes, a plurality of springs is provided for urging the plugs in a direction to continuously urge the vanes in an outward direction. A spring 76 is positioned within the bore 77 provided in one end of the rotor 25, one end of the spring 76 engaging an adjusting screw 78 which threadedly engages the bore 77 while the opposite end

of the spring engages a friction button 79 which in turn engages the actuator plug 73 for urging the same in a rightward direction as viewed in Figure 2.

A spring 80 is positioned between the actuator plugs 73 and 74 and has the opposite ends thereof engaging the friction buttons 81 and 82 which in turn engage the plugs 73 and 74 respectively. The spring 80 has less expansive force than the spring 76 and therefore will not effect the action of the spring 76 upon the plug 73. The spring 80 however does urge the actuator plug 74 in a rightward direction. A similar spring assembly 83 is provided between the actuator plugs 74 and 75 for urging the plug 75 in a rightward direction.

A spring 84 is positioned within a bore 25 provided in the drive shaft end of the rotor 25 for urging the actuator plugs 73, 74 and 75 in a leftward direction when the screw 78 releases pressure upon the spring 76 occasioned by the necessity of a repair operation to the pump.

The fluid or liquid pump 10 is of the variable delivery type wherein the rotor of the pump is mounted upon a permanent axis for rotation therein, while the cylinders cooperating with the rotors are movable with respect to the axis of the rotor to change the eccentricity between the rotor and the cylinder and thereby vary the volume of fluid discharged from the pump. The cylinders 37, 38 and 39 are slidably mounted in the manner which has heretofore been described to permit movement thereof with respect to the rotor 25. The eccentric position of the cylinders 37 and 39 with respect to the rotor 25 is 180° opposite to the eccentric position of the cylinder 38. Therefore, the fluid inlet and discharge ports for the cylinders 37 and 39 will be 180° from the corresponding fluid inlet and outlet for the cylinder 38. The purpose of this eccentric arrangement of the cylinders will be hereinafter more fully described.

To change the volume of fluid discharged from the various cylinders the cylinders 37 and 39 must be moved in a direction opposite to that of the cylinder 38 since their eccentricities are 180° away from that of the cylinder 38.

The mechanism for controlling the volume of the flow of fluid from the pump 10 consists of a threaded stem 86 which is in threaded engagement with the casing 11 having a threaded opening 87. The inner end of the stem 86 carries an enlarged head 88 which is retained within a recess 89 provided in the wall of the cylinder 38 by means of a plate 90 secured to the cylinder 38 by means of the bolts or screws 91. The outer end of the stem 86 is provided with an operating wheel 92 for rotating the stem within the threaded opening 87 and thus moving the cylinder 38 with respect to the rotor 25 to change the eccentricity therebetween.

The cylinders 37 and 39 are provided with actuating pins 93 and 94 respectively which are in slidable engagement with the holes 95 and 96 provided in the casing 11. The inner ends of the pins 93 and 94 are provided with enlarged heads 97 and 98 which engage the cylinders 37 and 39 and are retained in position in the same manner as the head 88. The outer ends of the actuating pins 93 and 94 are provided with annular recessed portions 99 and 100 respectively. A pair of levers 101 and 102 are pivotally mounted upon the pivot pins 103 and 104 respectively carried within ears 105 and 106 secured to the casing 11. The lever 101 is provided with a yoke 107 which engages the recess 99, while the op-

posite end of the lever is provided with a yoke which engages a reduced diameter portion 109 provided on the stem 86. The lever 102 is provided with a yoke 110 which engages the recess 100 of the actuating pin 94 and has a yoke 108a on the opposite end thereof similar to the yoke 108 of the lever 101 for engaging the recess 109. It may be seen from the drawings that when the stem 86 is moved in one direction or the other that the actuating pins 93 and 94 will move in a direction opposite to the direction of movement of the stem 86 so that the cylinders 37 and 39 will have their eccentric position changed relative to the rotor 25 in a direction opposite to the change of eccentric position of the cylinder 38 with respect to the rotor 25.

Since the cylinders of the pump 10 are capable of movement with respect to the rotor 25 the volume of fluid discharged by the pump can be varied from a minimum to a maximum and by shifting the eccentricity of the cylinders 180° with respect to the rotor 25 the direction of flow of fluid through the pump can be changed.

The pump 10 is provided with port passages 25 which can be used either as inlet or discharge passages depending upon the eccentric position of the cylinders with respect to the rotor 25. A port passage 111 in the base or closure member 15 communicates with a passage 112 provided in the cylinder 38. A similar port passage 113 in the casing 11 communicates with a passage 114 provided in the cylinder 38, the passage 114 being positioned 180° from the passage 112. These passages provide the fluid flow conduits through the cylinder 38 and communicate with the cylinder bore 45 thereof. The cylinders 37 and 39 have similar fluid flow passages. As seen in Figure 1 the conduit 115 which connects with the port passage 111 of the cylinder 38 also connects to the port passages 113 of the cylinders 37 and 39 but 180° from the port passage 111. A conduit 116 connects with the port passage 113 of the cylinder 38 and also to the port passages 111 of the cylinders 37 and 39. It may thus be seen that the discharge ports for the cylinders 37 and 39 are 180° from the discharge port for the cylinder 38.

A suitable motor 117 is connected to the drive shaft 21 of the pump 10 for driving the same.

The pump as herein described is constructed and arranged to balance the transverse thrust upon the bearings 19 and 20. When fluid is compressed within a compression chamber of a rotary pump the pressure of the fluid urges the rotor of the pump in a direction transverse to the axis of the rotor. The bearings which support the rotor are thus loaded upon one side thereof, which load upon the bearing occurs substantially opposite to the discharge opening of the cylinder within which the rotor is operating. The pressure within the compression chamber thus causes the development of a transverse force which normally in rotary fluid pumps cannot be offset when a single pumping chamber is utilized.

In this invention there is provided three pump units each consisting of a rotor and a cylinder, the rotors being of the same diameter and the cylinders being of equal diameter. Two of the rotors and cylinders have displacement areas which are half as wide as the third rotor and cylinder so that the surface areas of the rotors of the two smaller pumping units will be equal to the surface area of the large pumping unit. The small pumping units are positioned at opposite ends of the large pumping unit and since all of

the rotors of the pumping units are assembled into a composite structure, the forces developed within each of the pumping units will be transmitted through the rotor to the bearings supporting the same. The compression chambers of the two small pumping units are located 180° about the circumference of the rotor from the compression chamber of the large pumping unit. This arrangement is such that the transverse force developed within the two small pumping units will oppose the transverse force developed within the large pumping unit. Since the compression chambers of the large and small pumping units are 180° from each other, and since the small pumping units are positioned adjacent opposite ends of the large pumping unit, the transverse forces developed by the units will balance each other so that the resultant force applied to the bearings supporting the rotor is substantially a neutral force.

The analysis of the forces developed within the rotary pump is diagrammatically illustrated in Figures 4 and 5. In Figure 4 the arrows A indicate the direction of rotation of the three pump units. In this analysis diagram the pumping elements 31 and 33 have their discharge passages 118 positioned at the lower side of the pump so that the transverse force developed as a result of the compression of fluid passing through the pump is in the upward direction as indicated by the arrows B. The pumping element 32 is provided with its discharge passage 118 at the upper side of the unit so that the transverse force developed by the pumping unit 32 is in a downward direction as indicated by the arrow C. As previously mentioned the diameter of the cylinder bores for the pumping units 31, 32 and 33 is equal as is the diameter of the rotors for these cylinders. However, the length of the rotor for the pumping unit 32 is twice the length of the rotors for the pumping units 31 and 33, hence the transverse force developed by the pumping unit 32 will be double the magnitude of the force developed by either of the pumping units 31 and 33. However, since the transverse forces developed by the pumping units 31 and 33 are applied to the composite rotor in a direction opposite to the transverse force of the pumping unit 32 the resultant effect is to produce a condition of balanced forces so that there is no transverse thrust transmitted to the bearings which support the rotor.

In Figure 5 there is shown the same type of diagram as shown in Figure 4 but having the vanes of the pumping units advanced slightly in their rotative position with regard to the inlet and outlet ports for the cylinders. It will be noted that the position of the direction of the transverse forces developed within the pump have been changed slightly but these forces still apply themselves to the rotors in opposite and substantially parallel directions. The shift in the forces is due to the fact that the surface area exposed to the pressure has shifted to the left in the pumping units 31 and 33 while the surface area exposed to the pressure has shifted to the right in the pumping unit 32. In Figure 5 the surface area of the rotor of the pumping units 31 and 33 exposed to the pressure extends from the vane 34a to the vane 34b of the pumping unit 31 and from the vane 36a to the vane 36b upon the pumping unit 33, the resultant pres-

sure on the rotor being represented by the arrow B. The surface area of the rotor for the pumping unit 32 which is exposed to the pressure in the pumping unit 32 is from the vane 35a to the vane 35b so that the resultant pressure C is in the direction indicated by the arrows so marked.

It may thus be seen that even though the direction of the forces tends to shift slightly during rotation of the rotor that the forces will always maintain a balanced condition.

While in the description of this invention it has been specifically mentioned that the rotor of the pumping unit 32 is twice the width of the rotors for the pumping units 31 and 33 in order to provide a balanced force condition when the cylinders are of equal diameter yet the same results can be obtained by properly proportioning the diameters of the cylinder and rotors with respect to one another and decreasing or increasing the respective lengths of the rotors to compensate for the difference in diameters of the cylinders, the necessary result being that the transverse forces produced within the pumping units 31 and 33 shall be equal to the transverse force developed within the pumping unit 32 and be applied to a common drive shaft in the opposite direction to the direction of application of the transverse force of the pumping unit 32.

Having thus fully described my invention, what I claim as new and desire to secure by Letters Patent is:

A liquid pump of the vane type comprising a plurality of independent cylinders including a central cylinder and a cylinder adjacent each end of said central cylinder having an internal surface area less than the internal surface area of said central cylinder, a rotor associated with each of said cylinders, said rotors being secured together to form a unitary rotor assembly, bearing means for said rotor assembly positioned at opposite ends of said rotor assembly for supporting the same, each of said rotors including vanes for association with thin respective cylinders to provide a plurality of pump units, means for eccentrically positioning said cylinders with respect to said rotors, said end cylinders having the compression chambers thereof disposed diametrically opposite to said central cylinder, said end cylinders having their compression chambers so proportioned to the compression chamber of said central cylinder that the transverse forces produced within said end cylinders upon said rotor assembly are substantially equal to each other and the combined forces are equal to the transverse forces produced within said central cylinder and applied upon said rotor assembly in a diametrically opposed direction to thereby balance all forces upon said rotor assembly, and means including means, connected with said eccentrically positioning means, for adjusting said end cylinders and said central cylinder in diametrically opposite directions for simultaneously changing the eccentricity of adjacent cylinders with respect to said rotor in opposite directions, said eccentric adjusting means further including an adjustable stem member engaging said central cylinder and adjustably engaging said casing, and a pair of oppositely extending links attached at one of their ends to said stem member, the opposite ends of each of said links being connected to an end cylinder.

WARREN R. TUCKER.
